UNITED STATES PATENT OFFICE.

GEORGE C. KNAUFF, OF CHICAGO, ILLINOIS.

ELECTRIC-LAMP SOCKET.

1,109,633.

Specification of Letters Patent. Patented Sept. 1, 1914.

Application filed November 14, 1913. Serial No. 800,943.

To all whom it may concern:

Be it known that I, GEORGE C. KNAUFF, a citizen of the United States, residing at Chicago, in the county of Cook and State of Illinois, have invented certain new and useful Improvements in Electric-Lamp Sockets; and I do hereby declare the following to be a full, clear, and exact description of the invention, such as will enable others skilled 10 in the art to which it appertains to make and use the same.

My invention relates to sockets for incandescent lamps, and to means for securing such a socket simultaneously to a reflector 15 and a handle to constitute a portable or so-called "trouble finder" lamp.

It has become customary for owners of automobiles equipped with electrical head and tail lamps to utilize the available current for 20 lighting a portable lamp so as to illuminate any desired parts of the mechanism of the automobile, the light being concentrated in the desired direction by a reflector mounted close to the portable lamp.

One object of my invention is to provide 25 simple means for simultaneously securing a lamp socket and a suitable reflector to a handle by which the lamp may be manipulated, and for insulating the metal socket 30 parts from the reflector.

Another object is to provide a construction enabling the socket to be easily wired.

Still another object is to provide a stop 35 formation upon a socket casing which may be used in any desired connection where a socket is to be rigidly mounted upon a support.

In the drawings, Figure 1 shows a longitudinal section through a portable lamp 40 equipment embodying my invention. Fig. 2 is an end view of Fig. 1 with the lamp omitted. Fig. 3 is a fragmentary elevation of the end of the socket coupled to the lamp. Fig. 4 is an enlarged fragmentary section of 45 the casing of the socket, showing the method of forming the stop formation. Fig. 5 is a fragmentary section showing another method of fastening the main and auxiliary casings of the socket to each other. Fig. 6

is a fragmentary view showing the auxiliary 50 casing slid out of its normal position to facilitate the wiring of the socket.

In the drawings, the handle 1 is equipped with a differential bore extending longitudinally thereof, the larger bore being approximately equal to the outer diameter of the metal casing 2 of the lamp socket, which casing is equipped at its forward end with bayonet slots 3 coöperating with projections 4 upon the base of the lamp 5 to couple the 60 said lamp to the casing. The rear end of the casing 2 is equipped with a tubular extension 6, preferably of a smaller diameter than the main casing 2, which extension has at its rear end a threaded portion 7 engaging threads upon a bushing 8 housed at the rear end of the handle 1. Intermediate of the rear end of the bayonet slots 3 and the forward end of the handle 1, the casing 2 is equipped with a lateral flange 9, which 70 flange is formed integral with the casing radially distending the adjacent portions of the casing and longitudinally compressing the casing. Interposed between the said flange and the adjacent end of the handle 1 75 are an insulating washer 10 and the rear end of a reflector 12, the said washer having a bore corresponding to the casing 2 and a periphery engaging the shoulder portions 11 of the reflector at the juncture of the lateral wall thereof with the rear end thereof. The said rear end of the reflector is preferably considerably larger in bore than the outer diameter of the casing 2 so as to be 80 out of contact with the latter, thereby enabling the washer 10 to insulate the reflector from the inner wall, while the interfitting of the washer with the casing and the shoulder portion of the reflector respectively will hold the said parts in their normally spaced 85 relation. The lamp 5 has its base equipped with a metal shell 13 and with an axially disposed contact 14 insulated therefrom, the said shell and contact being respectively connected to the ends of the lamp filament. 90

Mounted within the main casing 2 and slidably fitting the interior thereof is an auxiliary casing 15 housing an insulating 95

tube 16. Mounted within this tube is a wire terminal 17 equipped at its forward end with a plunger 18 projecting therefrom and contacting at its forward end with the said axially disposed contact 14 and continuously pressed against the latter by a spring 19 housed within the said wire terminal 17. The auxiliary casing and the parts carried thereby are normally secured within the main casing 2 by a screw 20. Upon removing this screw, the auxiliary casing may be slid out of the main casing, as shown in Fig. 6, thereby permitting the terminals 21 and 22 of the circuit to be secured respectively to the wire terminals 17 and the auxiliary casing 15. When the body portion of the socket has been thus wired, it can readily be slid to its normal position and secured therein either by a screw 20, or by forming indentations 23 in both the casings, as in Fig. 5.

It will be evident from the drawings that by rotating the casing of the socket and the tubular extension thereon with respect to the bushing or nut 8, the threaded connection between the latter and the extension 6 will move the casing longitudinally of the handle so as to draw the flange 9 into forcible abutment with the washer 10, thereby locking the reflector 12 between the said washer and the handle 1 and securing the socket and reflector members of my appliance simultaneously and rigidly to the handle thereof.

It will also be evident from Fig. 6 that the socket of my invention can easily be wired by an ordinary workman even if made in the miniature corresponding to the lamps commonly used in automobile lighting, and that the integral flange formation upon the socket casing will afford a simple method of anchoring the latter without the use of auxiliary parts. However, I do not wish to be limited to the precise details of the construction herein disclosed, as the same might be modified in many ways without departing from the spirit of my invention as shown in the appended claims.

I claim as my invention:

50. 1. A socket for a lamp having its filament terminals connected respectively to a shell and an axially disposed contact, including a casing equipped with means for coupling the lamp thereto, an axially disposed wire terminal housed by the casing and insulated therefrom, and a cylindrical wire terminal interposed between the aforesaid wire terminal and the casing and contacting with the latter to carry current thereto, the said cylindrical wire terminal slidably interfitting the casing and being movable beyond the end of the said casing to permit access to both wire terminals for attaching wires thereto.

65. 2. In a socket, lamp and reflector com-

bination, a tubular handle, a centrally perforated reflector disposed at one end thereof, contact members housed by the said tubular handle and connected to the terminals of a circuit; a tubular member comprising in integral formation a shell equipped with means for coupling the said lamp thereto, a casing interposed between an end portion of the said handle and the said contact members and contacting with one of the latter, and an extension upon the said casing extending approximately to the other end of the said handle; an insulating washer housed by the reflector, there being an enlargement upon the tubular member interposed between the said shell and casing and engaging the said washer; and means co-operating with the said handle and tubular member for forcing the said enlargement against the said washer to simultaneously fasten the handle to the reflector and the tubular member.

3. In a socket for an electric lamp equipped upon its base with a shell and an axially disposed contact connected respectively to the ends of the lamp filament, the combination with a tubular casing having one end slidably fitting the said shell of the lamp and equipped at its said end with means for coupling the casing to the lamp, of an auxiliary casing slidably and contactingly fitting the interior of the tubular casing and connected to one terminal of a circuit, an insulating body mounted in the auxiliary casing, a wire terminal carried by the insulating body and connected to the other terminal of the circuit, an extension carried by the said wire terminal and contacting with the said axially disposed contact, and a spring interposed between the said extension and the wire terminal carrying the same, and pressing said extension against the said contact.

4. In a lamp socket, the combination with a tubular support, of a socket casing housed by the said support and projecting at one end beyond the said support and equipped at its said end with means for coupling a lamp thereto, the said casing equipped adjacent to the said coupling means with a lateral flange engaging the adjacent end of the said tubular support; means threaded upon the other end of the said casing and engaging the tubular support and coacting with the latter to force the said flange against the end of the tubular support adjacent to the latter, thereby rigidly securing the said casing to the said support; and wire terminals carried by the said casing and contacting with the terminals of the said lamp.

5. A lamp socket including a casing and a tubular support therefor, the said casing equipped both with an extension housed by the said tubular support and with a lateral

flange formed by radially distending and longitudinally compressing a portion of the said casing; and means carried by the said extension and coacting with the said support to move the said extension and casing relatively to the said support to clamp the said support therebetween.

In testimony whereof I have signed my name in presence of two subscribing witnesses.

GEORGE C. KNAUFF.
